Inventor:

Konrad Jagschitz

UNITED STATES PATENT OFFICE.

KONRAD JAGSCHITZ, OF MAINZ, GERMANY, ASSIGNOR TO MASCHINENFABRIK AUGSBURG-NUERNBERG, A. G., OF NUERNBERG, BAVARIA, GERMANY, A CORPORATION OF GERMANY.

SEALING-LIQUID-COLLECTING TANK FOR DISK-TYPE GASOMETERS.

Application filed July 7, 1923. Serial No. 650,022.

To all whom it may concern:

Be it known that I, KONRAD JAGSCHITZ, a citizen of the Republic of Austria, and a resident of Mainz, Germany, have invented 5 certain new and useful Improvements in Sealing-Liquid-Collecting Tanks for Disk-Type Gasometers, of which the following is a specification.

This invention relates to gasometers of 10 the disk type, that is to say, in which the variable gas space is closed up by a disk sliding gas-tight upon the inner wall of the gasometer.

In this type of gasometer the gas-tight 15 seal between the wall of the gasometer and the sliding disk is formed by a liquid filling the narrow gap existing between the disk and the wall, and it has been found, that the most efficient way of sealing is to keep the 20 liquid continuously running down the wall of the gasometer, the liquid being eventually collected at the bottom and returned into the distributor at the top of the gasometer in order to be used again.

25 The main object of the invention now is to provide efficient and improved means for facilitating the collection and reemployment of the sealing liquid.

Further objects are the separation of undesirable matter from the sealing liquid 30 while collecting, and the prevention of freezing or congealing of the sealing liquid or the water separating therefrom.

According to the invention collecting 35 tanks are provided in close proximity to the walls of the gasometer at the foot thereof and communicating with the same by means of a dip tube extending down to a relatively great depth below the liquid level in the collecting tank. The diameter of these dip tubes is such as to allow of all undesirable matter specifically lighter than the sealing liquid, water for example, to accumulate at the top, whence it may be removed through 45 a tap hole provided for the purpose.

In order to be able to remove the water 50 in freezing weather, which ordinarily would be impossible owing to the difficulty of separating the ice crystals respectively, from the viscous gas tar generally employed as the sealing medium, heating devices are employed which preferably consists of an ordinary tube arranged to extend across the

collecting tank and heated by a jet of gas drawn directly from the gasometer. 55

Modern gasometers are often of very large dimensions; subsidences are likely to occur with the result that the liquid would collect at one side of the gasometer only, and in order to prevent this drawback, a turnable flap or gate is provided at the upper edges of the dip tubes, which may be operated from the outside and whereby the overflow edges of the said tubes may be raised or lowered as required. 60

Further objects and advantages of the invention will be apparent from the following description of the accompanying sheet of drawings, in which the invention is illustrated by way of example. 65

In these drawings,

Fig. 1 is a vertical section through one of the sealing liquid containers which, according to the invention, are spaced at convenient intervals around the gasometer. 70

Fig. 2 is a sectional plan view of the container or tank.

Figs. 3 and 4 are detail front and side elevations respectively illustrating the adjustable overflow for the liquid at the top edges 75 of the dip tubes.

According to these figures the liquid container is arranged in close proximity to the gasometer *a* at the foot thereof. As will be seen from the drawing the gasometer is 80 built up of plate metal and the collecting tank *b* communicates with the same by means of dip tube *c* of comparatively large diameter which at one of its ends projects into the gasometer through the bottom thereof, whilst with its other end it is arranged to extend down into the liquid collecting tank to almost the bottom of the same. The sealing liquid is distributed at the top of the gasometer and allowed to continuously run 85 down the gasometer walls through the gap between the said walls and the sliding disk already referred to and which is not shown in the drawing as it forms no part of the invention. The liquid accumulates at the 90 bottom of the gasometer and eventually passes through the dip tubes *c* into the collecting tank *b*.

As will be seen from the drawing, the liquid level in the dip tube, by reason of 95 the gas pressure, will be somewhat lower

than in the tank itself, and the water or other undesirable matter separating therefrom will thus accumulate at the surface, being specifically lighter than the sealing liquid which generally consists of heavy gas tar. From here the water or other undesirable matter may be drained off through a suitably positioned tap hole *e*. The latter, as shown in Fig. 1, is located at a place corresponding to the level of the liquid in the dip tube *c*.

Within the tank *b* and outside the dip tube *c*, a float *f* is arranged which, by means of a link gear *f'*, is adapted to control an electric motor, or other means, provided to drive a liquid circulating pump which is arranged in any well known manner to return the sealing liquid which has collected in the tank *b* to the distributor generally located at the top of the gasometer. As the electric motor and circulating pump per se form no part of the invention, it has not been considered necessary to illustrate the same. The said pump is set in motion each time the sealing liquid has reached a certain level in the tank and is stopped as soon as sufficient liquid has been pumped up into the distributor at the upper part of the gasometer, whence it is allowed to run down the walls of the latter as already described. It will thus be seen that the float *f* and the link gear *f'* constitute means operated automatically by the variations in the liquid level in the collecting tank *b* for controlling withdrawal of sealing liquid therefrom.

In order to enable such tapping of the water accumulating in the collecting tank to be effected also in freezing weather and to thus avoid disturbances in the circulation of the sealing liquid, a heating tube *g* is arranged to extend across the collecting tank. A gas jet *h'* burning within this tube is fed directly from the gasometer through the pipe *h*.

For reasons described in the opening paragraphs of this specification the overflow from the gasometer *a* into the dip tube *c* is made to be adjustable in height. For this purpose a segment-shaped flap or gate *k* is mounted fluid-tight in a notch *i* at the upper end of the dip tube *c* (Figs. 3 and 4). This gate operates in the fashion of an overflow weir and can be adjusted from the outside by means of a lever *m* as shown in Figs. 3 and 4. By means of this device the height of the overflow edge may be varied and the flow of the sealing liquid into the collecting tank regulated. The exact position of the gate is indicated at the outside by the lever *m* functioning as a pointer and which may be arranged to move over a graduated scale *m'*.

The number of liquid collecting tanks required for a gasometer largely depends on the size of the latter. It must be such as

to insure a reliable collection and discharge of the sealing liquid on the one hand, and a satisfactory supply of the liquid between the closing disk and the gasometer wall at the other hand.

In order to achieve the aforesaid object with certainty, each of the collecting tanks is preferably in connection with a separate pump for the circulation of the liquid. In this way the proper collection and circulation of the liquid may be relied upon and the installation yet be easily supervised.

What I claim is:

1. The combination of a disk type gasometer and a collecting tank for collecting the sealing liquid, a dip tube, the upper end of which tube communicates with the gasometer and the lower end of which tube projects below the surface of the liquid collected in said tank, the wall of said dip tube intermediate the ends thereof being provided with a tap hole for the withdrawal of undesirable matter from said liquid and means operated automatically by the variations of the liquid level in said tank for controlling withdrawal of sealing liquid therefrom.

2. The combination of a disk type gasometer and a collecting tank for collecting the sealing liquid, a dip tube of comparatively large diameter, the upper end of which tube communicates with the gasometer and the lower end of which projects below the surface of the liquid collected in said tank, the wall of said dip tube being provided with a tap hole at a place corresponding to the liquid level in the tube for the discharge of undesirable matter, a float mounted within said tank and means connected with said float and operated thereby to control the withdrawal of sealing liquid from said tank.

3. The combination of a disk type gasometer, and a collecting tank for collecting the sealing liquid, characterized by the provision of a dip tube the upper end of which communicates with said gasometer and the lower end of which extends below the surface of the liquid collected in said tank, the wall of said dip tube being provided with a tap hole, and means to heat the liquid in said tank comprising a tube extending across said tank, and a pipe connection between the gasometer and said heating tube, providing gas for a gas jet within said heating tube.

4. The combination of a disk type gasometer, and a collecting tank for collecting the sealing liquid, characterized by the provision of a dip tube the upper end of which communicates with said gasometer and the lower end of which extends below the surface of the liquid collected in said tank, the wall of said dip tube being provided with a tap hole, and adjustable means

located at the upper end of said dip tube to control the overflow of liquid from said gasometer to said dip tube.

5. The combination of a disk type gasometer, and a collecting tank for collecting the sealing liquid, characterized by the provision of a dip tube the upper end of which communicates with said gasometer and the lower end of which extends below the surface of the liquid collected in said tank, the wall of said dip tube being provided with a tap hole, the upper end of said dip tube being provided with a recess, a turnable weir-like gate mounted in said recess to raise and lower the overflow edge of said tube and means operable from without the gasometer to turn said gate.

15 6. The combination of a disk type gasometer and a collecting tank for collecting the sealing liquid, a dip tube of comparatively large diameter, the upper end

of which tube communicates with the gasometer and the lower end of which projects below the surface of the liquid collected in said tank, the wall of said dip tube being provided with a tap hole at a place corresponding to the liquid level in the tube for the discharge of undesirable matter, a float mounted within said tank, means connected with said float and operated thereby to control the withdrawal of sealing liquid from said tank, and heating means connected with said gasometer and supplied with gas therefrom for heating the liquid within said tank.

30 35 In testimony whereof I affix my signature in presence of two witnesses.
